(57) **CLAIM**

The ornamental design for a carrying vest, as shown and described.

DESCRIPTION

FIG. 1 is a rear, exterior view of the carrying vest in an open configuration.

FIG. 2 is a front, interior view of the carrying vest shown in FIG. 1 in the open configuration.

FIG. 3 is a front view of the carrying vest shown in FIG. 1 in a closed configuration.

FIG. 4 is a rear view of the carrying vest shown in FIG. 1 in the closed configuration.

FIG. 5 is a first side view of the carrying vest shown in FIG. 1 in the closed configuration.

FIG. 6 is a second side view of the carrying vest shown in FIG. 1 in the closed configuration.

FIG. 7 is a bottom view of the carrying vest shown in FIG. 1 in the closed configuration; and,

FIG. 8 is a top view of the carrying vest shown in FIG. 1 in the closed configuration.

The broken lines in the Figures show portions of the design that form no part of the claim.

1 Claim, 5 Drawing Sheets
